UNITED STATES PATENT OFFICE

2,119,160

TOOTH POWDER CONTAINER

Charles S. Gringler, Cleveland, Ohio

Application May 12, 1937, Serial No. 142,298

2 Claims. (Cl. 221—112)

This invention relates to new and useful improvements in tooth powder containers.

One object of my invention is to provide a container of the character specified that will release just the proper amount of powder, at each operation, for cleaning the teeth.

A further object of my invention is to provide a tooth powder container, in which provision is made for depositing the correct amount of powder for cleaning the teeth, directly on the tooth brush, and without spilling any of the powder, as distinguished from the unsatisfactory methods now commonly employed of first emptying a quantity of powder in one hand and placing it on the tooth brush with the other hand.

With the foregoing and other objects in view that will appear as the nature of my invention is better understood, the same consists in the novel features of construction, combination and arrangement of parts illustrated in the accompanying drawing and more particularly pointed out in the appended claims.

In the accompanying drawing, which is for illustrative purposes only and is therefore not drawn to scale:

Figure 1 is a side elevation, partly in section, of a tooth powder container constructed in accordance with my invention.

Figure 2 is a vertical transverse section, taken on line 2—2 of Figure 1.

Figure 3 is a horizontal section, taken on line 3—3 of Figure 2.

Figure 4 is a rear elevation, partly in section, of a tooth powder container of the stationary or wall type, and Figure 5 is a vertical transverse section, taken on line 5—5 of Figure 4, looking in the direction indicated by the arrows.

Referring to the drawing for a more particular description of my invention, and in which drawing like parts are designated by like reference characters throughout the several views, the numeral 1 represents the cylindrical body of the container and 2 the cover or lid.

In carrying out my invention, the lid 2 is formed on its outer face with a central longitudinally disposed neck 3, of substantially hollow elliptical form in cross section, divided by the straight flat horizontal wall or partition 4, into the upper powder compartment 5 and the lower larger tooth brush receiving compartment 6. The partition 4 is formed at one side with an elongated longitudinal slot or opening 7, normally covered by the flat strip or shuttle 8. The strip or shuttle 8 is formed at its inner end with a transverse sliding arm 9, which works against the inner face of the lid 2. The arm 9 is equipped with a suitable handle or knob 10 for

the convenience of the operator, and the stem 11 of this knob works in a corresponding slot 12 in the lid. The inner end of the arm 9 is provided with a cover plate 13, adapted to close an opening 14 in the lid 2, which communicates with the inner end of the powder compartment 5. The cover plate 13 works in a rectangular housing 15, secured to the inner wall or face of the lid and formed with an opening 16 disposed in registration with the opening 14 aforesaid. 10 The compartment 6 is open at its outer end, as at 17, to receive the head of the tooth brush.

In practice, the head of the tooth brush is first inserted in the compartment 6, and the shuttle 8 is then shifted on the partition 4 to uncover the slot or opening 7. This operation releases just the proper amount of powder for cleaning the teeth, on the brush. When the shuttle 8 is shifted to the right to uncover the slot or opening 7, the cover plate 13 simultaneously covers 20 the openings 14 and 16.

In the stationary form of my invention illustrated in Figures 4 and 5 of the drawing, the container is mounted in a cylindrical housing 18, fastened by screws 19 or other equivalent means, 25 to the wall or other support. In this instance, the slot 20 in the upper wall 21 of the brush compartment 22, is normally closed by the shuttle 23, equipped with the operating handle 24.

From the foregoing description, taken in connection with the drawing, it is thought that the construction, operation and advantages of my invention will be readily understood, without requiring a more extended explanation.

Having described my invention, what I claim 35 as new and desire to secure by Letters Patent, is:

1. In a tooth powder container of the character specified, a body, a lid for the body and a hollow neck carried by the lid, said neck formed with a longitudinally disposed slotted partition 40 whereby it is divided into an upper powder compartment and a lower brush receiving compartment and a manually operated shuttle for opening and closing the slot in said partition, substantially as and for the purpose specified. 45

2. In a tooth powder container of the character specified, a body, a lid for the body and a hollow elongated neck carried by the lid, said neck divided into an upper powder compartment and a lower brush receiving compartment by a longitudinally disposed slotted partition, and a manually operated shuttle for opening and closing the slot in said partition and simultaneously closing and opening the inner end of the powder 55 compartment.

CHARLES S. GRINGLER.
